UNITED STATES PATENT-OFFICE.

ERNEST BAUMGARTNER, OF FAIRVIEW, PENNSYLVANIA.

DEVICE FOR PROMOTING AND CONTROLLING COMBUSTION.

SPECIFICATION forming part of Letters Patent No. 705,635, dated July 29, 1902.

Application filed January 7, 1902. Serial No. 88,730. (No model.)

To all whom it may concern:

Be it known that I, ERNEST BAUMGARTNER, a citizen of the United States, residing at Fairview, in the county of Erie and State of Pennsylvania, have invented certain new and useful Improvements in Devices for Promoting and Controlling Combustion; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in devices for promoting and controlling combustion, and is designed to operate as a portion of a stovepipe-flue, and has for its object the supplying of a limited amount of air to 20 the top of the fuel in the stove after all of the ordinary draft-openings of the stove are closed and operates to produce a downward current of air in the back part of the flue and an upward current of the products of 25 combustion in the front and central part of the flue. The mechanism by means of which I accomplish these results is hereinafter set forth and described, and illustrated in the accompanying drawings, in which—

30 Figure 1 is a vertical section of a portion of a stovepipe or flue on the line $x-x$ in Fig. 3, embodying my invention. Fig. 2 is a vertical section of the same on the line $y-y$ in Fig. 3. Fig. 3 is a longitudinal section of the same 35 on the line $z-z$ in Fig. 2.

In the drawings illustrating my invention, A is a section of a stovepipe or flue, in which, above its junction with the stove, I secure a reduced section of flue B. This section B is 40 provided with collars C C' on its upper and lower ends, which closely fit the inside of the flue A, so as to leave an annular chamber D between the flues A and B and the collars C and C'. In this chamber D, on the opposite 45 sides thereof, I secure vertical partitions d , which extend upward from the collar C' nearly to the collar C, and in the front of the

flue A, I make an air-inlet opening E, which supplies air to said chamber D at one side of the partition d therein, and in the collar C' 50 at the rear of the flue I make openings c , so that air entering the opening E passes up around the reduced flue B and over the tops of the partitions d and down on the opposite sides of said partitions and out through 55 the holes c in the collar C' and downward in a separate air-current along the back of the flue to the top of the fuel in the stove, while the products of combustion pass upward through the front and central portions of the 60 flue in the usual manner. By means of this construction I am enabled to utilize the well-known features of an up and down draft in the same flue and utilize it to supply draft-air to the top of the fuel in a stove, so as to 65 promote a reduced and limited combustion of the fuel when all of the ordinary draft-openings of the stove are closed.

Having thus described my invention, so as to enable others to construct and use the same, 70 what I claim as new, and desire to secure by Letters Patent of the United States, is—

The combination of a stovepipe or flue, a reduced flue-section inserted therein, annular collars on the upper and lower ends of said 75 reduced flue-section fitting the inside of the pipe or flue in which it is inserted, vertical partitions at each side of the reduced flue extending from the lower collar nearly to the upper collar thereon, an air-inlet opening or 80 openings in the front of the pipe or flue, communicating with the space between the reduced flue-section and the outer flue at one side of said partitions, and an air-discharge 85 opening or openings, through the lower collar at the rear of the flue, on the opposite side of said partitions, substantially as and for the purpose set forth.

In testimony whereof I affix my signature in presence of two witnesses.

ERNEST BAUMGARTNER.
